DESIGN FOR A NURSERY CLOCK

Dewey M. Dow, Verona, N. J.

Application July 22, 1946, Serial No. 131,825

Term of patent 14 years

(Cl. D42—7)

To all whom it may concern:

Be it known that I, Dewey M. Dow, a citizen of the United States, residing at Verona, in the county of Essex and State of New Jersey, have invented a new, original, and ornamental Design for Nursery Clocks, of which the following is a specification, reference being had to the accompanying drawing, forming part thereof, in which:

Figure 1 is a front view of a nursery clock embodying my new design;

Fig. 2 is a side view of the same;
Fig. 3 is a rear view of the same; and
Fig. 4 is a plan view of the same.

I claim:

The ornamental design for a nursery clock as shown.

DEWEY M. DOW.
